(57) **CLAIM**

We claim the ornamental design for a bird feeder, as shown and described.

DESCRIPTION

FIG. 1 is a front perspective view of the bird feeder showing our design, according to a first embodiment;

FIG. 2 is a front perspective view thereof, showing the bird feeder in an installed condition on a window sill;

FIG. 3 is a front elevation view of the bird feeder of FIG. 1;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a front perspective view of the bird feeder showing our design, according to a second embodiment;

FIG. 10 is a front perspective view thereof, showing the bird feeder in an installed condition on a window sill;

FIG. 11 is a front elevation view of the bird feeder of FIG. 9;

FIG. 12 is a rear elevation view thereof;

FIG. 13 is a right side elevation view thereof;

FIG. 14 is a left side elevation view thereof;

FIG. 15 is a top plan view thereof;

FIG. 16 is a bottom plan view thereof;

FIG. 17 is front perspective view of the bird feeder showing our design, according to a third embodiment;

FIG. 18 is a front perspective view thereof, showing the bird feeder in an installed condition on a window sill;

FIG. 19 is a front elevation view of the bird feeder of FIG. 17;

FIG. 20 is a rear elevation view thereof;

FIG. 21 is a right side elevation view thereof;

FIG. 22 is a left side elevation view thereof;

FIG. 23 is a top plan view thereof;

FIG. 24 is a bottom plan view thereof;

FIG. 25 is a front perspective view of the bird feeder showing our design, according to a fourth embodiment;

(Continued)

FIG. 26 is a front perspective view thereof, showing the bird feeder in an installed condition on a window sill;
 FIG. 27 is a front elevation view of the bird feeder of FIG. 25;
 FIG. 28 is a rear elevation view thereof;
 FIG. 29 is a right side elevation view thereof;
 FIG. 30 is a left side elevation view thereof;
 FIG. 31 is a top plan view thereof; and,
 FIG. 32 is a bottom plan view thereof.
 The broken lines depict exemplary environment and components for purposes of illustration and form no part of the design claim.
